**GOVERNOR CONTROL TAMPER-PROOF COVER
FOR A VEHICLE ENGINE FUEL PUMP**

Ted E. Raby, Lubbock County, Tex., assignor to F.I.E.

Filed Oct. 29, 1974, Ser. No. 518,479

Term of patent 14 years

Int Cl. D15—01

U.S. Cl. D77—1 A

FIG. 1

FIG. 2

FIG. 3

FIG. 4

FIG. 5

FIG. 6

FIG. 7

FIG. 1 is a front elevational view of a governor control tamper-proof cover for vehicle engine fuel pump showing my new design; in association with a fuel pump which has been shown in broken lines for illustrative purposes only;

FIG. 2 is a front elevational view thereof to a larger scale;

FIG. 3 is a right side elevational view of FIG. 2;

FIG. 4 is a rear elevational view of FIG. 2;

FIG. 5 is a bottom plan view of FIG. 2;

FIG. 6 is a left side elevational view of FIG. 2;

FIG. 7 is a sectional view taken substantially on line 7—7 of FIG. 4; and

FIG. 8 is a top plan view of FIG. 2.

I claim:

The ornamental design for a governor control tamper-proof cover for a vehicle engine fuel pump, as shown.
